UNITED STATES PATENT OFFICE.

DAVID BAUM, OF LIVERMORE FALLS, MAINE.

SHOE LOCATOR FOR SHOE-TURNING MACHINES.

Application filed October 29, 1925. Serial No. 65,616.

My invention relates to a device applicable for use in connection with a machine for turning shoes and the like, a patent on which was granted me Nov. 17, 1925, numbered 5 1,562,282.

The principal object of my invention is to provide means to automatically position a shoe after it has been placed over the turning-tube and receding-plunger of the before-mentioned machine so that when the turning-plunger descends it will contact with the sole at the proper distance from the point or tip thereof and thereby prevent the toe end of the shoe projecting above or beyond the receding plunger overmuch, which condition would likely cause the sole to become wrapped around the end of the turning-plunger and produce a jam within the turning-tube.

Another object is to expand or widen the interior space at the toe end of the shoe which has the effect of limbering the sole and creating a condition favoring an easier start at the preliminary turning of the shoe.

A still further object of my invention is that it greatly expedites the work of properly positioning the shoe in the turning machine, due largely to the fact that with this improvement the operator is not required to expend as much time nor give as close attention to this particular detail in the operation of the machine as would otherwise be found necessary.

Hereinafter in this specification I have described, and in the drawings accompanying illustrated, so much only of my shoe-turning machine previously referred to, as will give a clear understanding of how my present invention functions in connection with the operation of that machine in the process of shoe-turning, and in the drawings which disclose the preferred embodiment of the invention, and in which like characters of reference indicate similar parts throughout all the different views.

Fig. 1 is a side elevation of my shoe-turning machine with my locator attached thereto;

Figs. 2, 3, 4, 5 and 6 are fragmentary sectional details showing, consecutively, different stages of the turning operation and the position of my locator at each stage;

Fig. 7 is a sectional view of the locator, taken on line 7-7, Fig. 2;

Fig. 8 shows an alternate method of

mounting the locator on the shoe-turning machine;

Fig. 9 shows an alternate method of operating the locator;

Figs. 10, 11, 12 and 13 are sectional details, showing the form of locator illustrated in Fig. 9 in different positions during the turning operation,

Figs. 14 and 15 are sectional views of the toe end of a shoe, illustrating the effect produced by the locator in widening the toe space of the shoe, and

Fig. 16 is a plan view of the locator shown in Fig. 9.

Fig. 1 illustrates in a condensed form the essential portions of my shoe-turning machine. 1 is the pedestal, secured to which by the screws 2 is the column 3. A bracket 4, fixed to the pedestal (1), carries the horizontally reciprocable slide 5 on which is superimposed the expansible turning-tube 6,—this latter enclosing the receding-plunger 7 which is mounted yieldingly within the tube. The turning-plunger 8, adjustably secured to and depending from the bracket 9 which is fixed to the rack-shaft 10, is adaptable of vertical reciprocation by means of the segmental gear 11 engaging the rack cut on the rack-shaft,—the actuating agent being the hand-lever 11'.

On the downward movement of the rack-shaft (10) the block 12 will, at the proper time, engage the roll 13 pivoted in a bearing in the slide 5, causing the latter to move and carry the turning-tube 6 into vertical alignment with the turning-plunger 8.

In Fig. 2 I illustrate portions of the turning-plunger 8, the receding-plunger 7 and the turning-tube 6, with my shoe locator mounted on the turning-plunger and a section of the toe end of a shoe 7' encompassing the receding plunger. The parts as shown illustrate the proper and normal positions of the turning elements previous to the turning operation,—or in other words in the in-operative position of all the parts.

When the turning-plunger (8) descends to a position shown in Fig. 3, and while yet in disalignment with the turning-tube (6), it abuts on the sole of the shoe near the toe end. The block 12 has at this point just come into contact with the roll 13 but the immediate, further downward movement of the rack-shaft 10 will force the slide 5 outwardly bringing the turning-tube 6 directly beneath 112

the turning-plunger 8,—the receding-plunger 7 taking on a two-way movement,—outwardly and downwardly.

The parts are now located as seen in Fig. 5. The next movement,—or more properly the continuation of the downward stroke of the turning-plunger (8) is portrayed in Fig. 6 which illustrates the toe end of the shoe just starting to be turned within the tube 6.

In practice, the operator will often place the shoe on the receding-plunger as it is shown in Fig. 4 in full lines. Here the point or tip of the shoe is too far advanced on the roll of the receding-plunger, and the turning-plunger, in case there was no provision made to prevent it, would abut on the sole a greater distance from the tip end, toward the heel, than would be desirable.

In my attempt to remedy this defect in the turning elements of the shoe-turner I have conceived the device which I call the shoe locator, identified by the reference character 14. It consists of a sleeve 14' with an apron or deflecting member 14'' depending from and extending outwardly of the sleeve and preferably somewhat curved in form. It is positioned, relative to the turning-tube so as to strike, when descending, the extreme tip of the shoe whenever the latter happens to be placed in the too far advanced position previously referred to. It may be pivoted, as seen at 25, so as to be adjusted to different angular positions, relative to the axis of the turning-plunger, and any change in the angular relation will correspondingly effect the extent of the rise of the sole above the receding-plunger.

In Fig. 4 the locator, shown in full lines, is represented as just coming into contact with the shoe when in the advanced position. On the continuing downward movement of the turning-plunger the deflecting member will have descended to the position shown in dot and dash lines (same figure) which will have moved the shoe backwardly from its advanced position to that shown in dot and dash lines,—or substantially the same position as it is shown in Figs. 2 and 3,—this position, however, being subject to change by adjusting the deflecting member to other angular positions.

Referring to Fig. 6, it will be observed that the turning-plunger (8) has entered the turning-tube (7), starting the preliminary turning of the shoe tip, and that in this position the function of the locator has been exercised and its duty fulfilled, and that for a time, or during the remainder of the turning operation it will remain in its present position by means which will be hereinafter disclosed.

It is obvious however, that, as the locator can move no further downwardly, some yielding means must be employed and co-action produced between the turning-plunger

and the locator whereby the former may continue its downward movement and complete the turning of the shoe.

I have, therefore, provided for this requirement by inserting in a bore 8' of the turning-plunger a helical spring 15, the upper end abutting on the plug 16 and the lower end thrusting on the washer 17 which is in contact with the pin 18. This pin (18) is fixed in the sleeve of the locator and reciprocates in the slots 19 cut in the tubular portion of the turning-plunger; it (18) thus serves to compress the helical spring 15 and also to act in holding the locator against rotation on the turning-plunger. While the ability of the locator to yield and recede over the turning-plunger when upward pressure or resistance is applied thereto is a feature employed principally to allow the turning-plunger to telescope the turning-tube and complete the turning, it also acts in the capacity of a buffer to cushion the impact of the locator against the shoe tip in the event that the shoe has been placed in the "too far advanced" position in the machine.

Reverting to Fig. 6 it will be clearly seen that further downward movement of the turning-plunger would, if no provision was made to guard against it, allow the locator to bear strongly against the shoe and prevent it turning easily over the edge of the turning-tube.

In Fig. 1 I illustrate my method of taking care of this situation. Extending outwardly from and fixed to the column 3 is a bracket 20, slidable in a hole 21 in which is a stop-rod 22, the lower end of which is secured in an off-set portion 23 of the locator and the upper end threaded to receive the nut 24.

When the turning-plunger 8 descends into the turning-tube 6 a distance such as is shown in Fig. 6, the nut 24 on the stop-rod 22 will have abutted on the bracket 20 and no further movement downwardly of the locator can take place. It is now in a position just clear of the shoe and remains thus during the turning operation.

By observing Fig. 1 it will be apparent that my shoe locator might be applied to the shoe turning machine in various other ways than the one I have just described and illustrated in my drawings, and still function in substantially the same manner. For instance, it might be mounted on the rack-shaft 10, or any element in the machine having reciprocating movement synchronizing with the movement of this shaft; or it might be installed somewhat after the manner of the locator shown in Fig. 8, which is shown as a manually operated device, but which, it is quite conceivable, might be made to operate automatically.

In all instances, however, the characteristic feature of the locator embodying the capacity to properly locate a shoe indiffer-

ently placed by the operator over the turning tube of the machine remains the same, whichever method of application may be adopted; and the two fundamental and essential features which reside in the device are its ability to come into accurate operative position at the proper time,—performing its function as the shoe locating agent, and then to withdraw from this position so as to be removed from all interference with the shoe while being placed in position on the machine.

In the shoe industry the demands of the trade necessitate frequent changes in the style of shoes. Oftentimes the model called for has a narrow, flat and pointed toe and with this style of shoe a slight modification in the design of my locator as hereinbefore described may be desirable; and while not absolutely necessary, I prefer to embody in this alternative design certain features which seem to assist in a measure to overcome some of the inherent difficulties met with in the turning of this particular style of shoe.

After a consideration of the description hereinafter contained it will be observed that generic characteristic features exist in both designs and that either might be employed and function properly in the shoe turning operation.

In Figs. 9 to 13 inclusive this modified form of locator is illustrated. The deflecting member is here hung pivotally at 25, from which point it may oscillate at certain times. The connection between the stop-rod 22 and the operating arm 26 of the deflecting member is also pivotal, as seen at 27. An ear 28, having an adjusting screw 28', restricts the oscillation of the deflecting member to a predetermined amount in one direction, and an ear 29, with an adjusting screw 29', serves in a like capacity, but in the opposite direction. A helical spring 30, mounted on the deflecting member pivot pin 25 holds this member (14") in its normal, inoperative position, as seen in Figs. 9, 10 and 11.

In describing the locator having the pivotally hung deflecting member, the sequence of movements may best be followed by observing in consecutive order the Figs. 9 to 13 inclusive. The shoe having been placed on the receding plunger 7 (see Fig. 9), the movement of the rack-shaft 10 will bring the turning-plunger 8 to the position seen in Fig. 10,—the deflecting member abutting on the end of the shoe. In Fig. 11 is seen the result of the next movement in operation which is to bring both plungers (7 and 8) into vertical alignment, one with the other, which move bends the tip of the sole slightly inward.

It might be well to explain, at this point, that it is desirable, if not quite essential, to flatten or broaden the tip of the shoe so as

to be better able to begin the turning as closely as possible to the toe end of the shoe. To do this would open or enlarge the narrow confined space at the end of the shoe, as in Fig. 14, and result in the form as seen in Fig. 15.

With this object in view I have pivoted the deflecting member at such a point on the sleeve of the locator as will, on the next, or continued movement of the turning-plunger downwardly, allow it to impinge strongly on the extreme point of the sole, rolling the latter over somewhat and tending to open or enlarge the space within the shoe.

It will be noticed in Fig. 11 that the stop-rod nut 24 is shown in contact with the bracket 20. This holds the pivoting point 27 fixed, relative to downward movement of the rod, but the fulcrum point of the deflecting member at 25 may descend further, and held at one end at the connecting point 27, the deflecting member may swing as the locator descends until the screw 28' contacts with the sleeve of the locator, as seen in Fig. 12. Thus suspended on the stop-rod 22 the locator remains until the turning-plunger has completed the turning of the shoe,—after which all parts rise to their normal or inoperative position, as seen in Fig. 9.

Having thus described my invention, what I claim is:

1. In a shoe turning machine, a reciprocable plunger, a deflector member yieldingly and oscillatively mounted on said plunger, means to actuate said plunger whereby said deflector member may be brought into engagement with the upper of a shoe, loosely positioned in said machine, for the purpose of automatically and positively positioning the shoe for the subsequent turning thereof.

2. In a shoe turning machine, a reciprocable plunger, a deflector member yieldingly mounted on said plunger, means to hold said deflector member, at predetermined times, at a spaced distance from the toe end of a shoe loosely mounted in said machine, means to bring said deflector member into contiguous and forcible relation with the shoe in said machine, and means whereby the contacting face of the said deflector member may be presented to the upper of the shoe at various, predetermined angular relations therewith.

3. In a shoe turning machine, a plunger reciprocably mounted on said machine, a deflector member slidably mounted on said plunger, yielding means acting to force said deflector member toward the end of said plunger opposite its fixed end, means to hold said deflector member from complete withdrawal from off said plunger, means to adjust said deflector member on said plunger so that that portion of its surface adapted to engage the toe of a shoe loosely positioned

in said machine may be presented to the shoe at various relative and predetermined angles therewith, and means to actuate said plunger.

5. In a shoe turning machine, a plunger reciprocable in said machine, a deflector member yieldingly mounted on said plunger, means to bring said deflector member alternately into and out of contact with a shoe placed in said machine, means to swivel said deflector member on and relative to said plunger, and means to limit the extreme movement of said deflector member toward the shoe on said machine.

5. In a shoe turning machine, a plunger reciprocable on said machine, a deflector member slidably mounted on said plunger, yielding means acting to force said deflector member off the free end of said plunger, means to cause said deflector member to swing on its pivotal point subsequent to its contacting with the toe of a shoe mounted in said machine, whereby it may act to bend the tip of the sole of the shoe, and means to vary, predeterminedly, the point at which the onward movement of said deflector member shall cease.

DAVID BAUM.
